(57) **CLAIM**

I claim the ornamental design for a field sensitive proximity switch housing, as shown and described.

DESCRIPTION

FIG. 1 is an isometric view of a first embodiment of a field sensitive proximity switch housing in accordance with my new design;

FIG. 2 is a front elevation of the field sensitive proximity switch housing shown in FIG. 1;

FIG. 3 is a right side elevation view of the field sensitive proximity switch housing shown in FIG. 1;

FIG. 4 is a top plan view of the field sensitive proximity switch housing shown in FIG. 1;

FIG. 5 is a bottom view of the field sensitive proximity switch housing shown in FIG. 1;

FIG. 6 is an isometric view of a second embodiment of a field sensitive proximity switch housing in accordance with my new design;

FIG. 7 is a front elevation of the field sensitive proximity switch housing shown in FIG. 6;

FIG. 8 is a right side elevation view of the field sensitive proximity switch housing shown in FIG. 6;

FIG. 9 is a top plan view of the field sensitive proximity switch housing shown in FIG. 6; and,

FIG. 10 is a bottom view of the field sensitive proximity switch housing shown in FIG. 6.

The front elevation is the same as the rear elevation for both embodiments. The left side elevation is the same as the right side elevation in both embodiments.
